[57] **CLAIM**

The ornamental design for a sump pump hose adapter, as shown and described.

DESCRIPTION

FIG. 1 is a front elevational view of the sump pump hose adapter of the present invention, the rear, top and bottom views being mirror images thereof;

FIG. 2 is a left side elevational view of the sump pump hose adapter of FIG. 1;

FIG. 3 is a right side elevational view of the sump pump hose adapter of FIG. 1; and,

FIG. 4 is a cross-sectional view of FIG. 3 taken along line 4—4 of the sump pump hose adapter.
